UNITED STATES PATENT OFFICE.

JOSEPH W. SCHLOSS, OF NEW YORK, N. Y.

FEATHERBONE-MAKING APPARATUS.

1,114,536.

Specification of Letters Patent. Patented Oct. 20, 1914.

Application filed April 7, 1914. Serial No. 830,130.

To all whom it may concern:

Be it known that I, JOSEPH W. SCHLOSS, a citizen of the United States, residing at the city of New York, in the borough of 5 Manhattan and State of New York, have invented certain new and useful Improvements in Featherbone-Making Apparatus, of which the following is a full, clear, and exact description.

- 10 My invention relates to the manufacture of featherbone, and particularly to apparatus for completing the manufacture after the quills have been bundled together into a strip and wound in the usual manner. 15 As is well known, the treatment of the strip in completing the manufacture entails three operations, first the sizing or subjecting the strip to a bath in a glutinous fluid, second, the drying of the sized strip, and 20 finally, the rolling and compressing of the dried strip into its final form.

A general object of my invention is to provide an apparatus for this purpose which will be simpler and more compact 25 than those in general use, and which will be more reliable in its operation. In the form heretofore used the apparatus has a sizing tank through which the strip is guided in a generally horizontal direction, 30 and a heated drying box having a slit in one end through which the sized strip enters after the surplus glue is removed, and having two power driven rollers over which the strip passes back and forth horizontally 35 until dried, and a rolling machine outside the box through which the dried strip passes after it comes from the box. The rolling machine is commonly provided with heated rollers between which the strip passes and 40 is heated as it is compressed.

The passage of the strip through the air after it emerges from the drying box, when it is momentarily more or less cooled, and then the sudden subjection of it to the relatively great heat of the rolling machine, frequently deleteriously affects the strip, rendering it brittle, and an object of my invention is to obviate this disadvantage.

I have found that a superior product can 50 be obtained if the strip is rolled while still at the temperature of the drying box before it is permitted to undergo any change in temperature, and I have further found that if this is done the heating may be dispensed 55 with during the rolling operation. In accordance with my invention, therefore, I

place the rollers of the rolling device inside the drying box in position to receive the dried strip as it comes off the drum, and the driving means for the rollers are preferably 60 outside the box and connected to the driving means for the drum so that the drum and rollers are driven at the same peripheral speed. In addition to rendering the device more compact and dispensing with heating 65 means for the rolling machine, this construction has the advantage of producing a more uniform and resilient article.

I shall now describe the embodiments of 70 my invention illustrated in the accompanying drawings, and shall thereafter point out my invention in claims.

Figure 1 is a side elevation of a complete 75 apparatus embodying my invention. Fig. 2 is a front elevation of the same with the reel removed and a portion of the front of the drying box broken away. Fig. 3 is a vertical sectional elevation, the section through the drying box being taken on line 3—3 of Fig. 2, and the section through the 80 sizing tank being taken on line 3a—3a of Fig. 2.

The sizing tank comprises an open receptacle 1 in which the sizing fluid is contained, the flanged ends of which rest upon a tank 2 which contains heated water. The water is poured in through a stand pipe 3 which communicates with a pipe 4 entering the tank, the height of the water in the tank being indicated by its height in the stand pipe 3. 90 In order to heat the water in the tank 2, two perforated gas pipes 5 are provided underneath the tank which connect with the common pipe 6 communicating through pipe 7 with the gas main 8, suitable cocks being 95 provided in the pipes 5 to control the flow of the gas. A door 2a affords access to the inclosed gas pipes 5 underneath the tank 2. A frame 9 rests upon the sides of the receptacle 1, being secured thereto by thumbscrews 10, and has three guide-rollers 11 disposed in the sizing fluid, under which the strip 12 passes and is thereby guided through the sizing bath.

In order to remove any surplus glue from 105 the material after passing through the bath, the strip passes through a suitable device such as a wringer, disposed on the sizing tank and in the form shown having two rubber rollers 13, the lower roller being 110 mounted in stationary bearings and the upper roller being mounted in bearing

blocks which are vertically slidable and are held down by the screws 14 which bear on the top of the adjustable bearings and serve to regulate the pressure between the two 5 rollers of the wringer.

After passing through the wringer, the sized strip enters the drying box 15 through a slit not shown in its front wall near the lower end at its right side. The drying box 10 is what I term an upright box, being considerably elongated and standing on end with its longest sides vertical, and is located adjacent the sizing tank. Two horizontal parallel drums extending substantially the 15 full width of the drying box are journaled in bearings on the sides of the drying box, one above the other, the lower drum 16 being disposed near the bottom, and the upper drum 17 being disposed near the top of the drying box. The lower drum 16 is power 20 driven being provided on the left end of its shaft outside the drying box with a pulley 18 which may be driven by a belt or in any other suitable way. The upper drum 17 25 may also be power driven but generally this is unnecessary.

The sized strip after entering the drying box is passed successively and continuously around the two drums, as shown, two suitable 30 guide members 19 being provided, one near each drum, which are attached at their ends to the sides of the drying box and have a plurality of fingers extending in the path of the strip and properly spacing the several 35 turns.

In order to remove any glue from the drum 16 which may have been transferred to its surface from the freshly sized strip, a 40 scraper 20 is provided which extends the length of the drum 16 and rests upon its periphery at such an angle as to scrape off the glue. This scraper 20 is attached to a transverse rock-shaft 21 journaled in the sides of the drying box, and a weighted 45 lever-arm 22 is attached to the rock-shaft so that its weight serves to yieldingly hold the scraper 20 against the surface of the drum 16.

In order to supply heat to the drying box 50 to dry the strip of material as it is rotated over the drums, a stand pipe 23 is provided along the vertical side of the drying box opposite the side at which the freshly sized strip enters. This stand pipe 23 has its 55 inner side perforated, as shown in Fig. 3, and communicates at its lower end with a pipe 24 leading from a gas heater 25. Air is drawn into this heater by a fan 26, and this air is heated by burning gas emerging 60 from a plurality of perforated pipes 27 at the bottom of the heater which communicate with the gas main 8, as shown in Fig. 2. It is apparent that the heated air will pass 65 through the upwardly-inclined pipe 24 and into the stand pipe 23 and thence through

the perforations into the drying box, this natural circulation being assisted by the fan 26. It will be noted that the strip as it 70 dries approaches the stand pipe 23 in its passage around the drums, and it is therefore subjected to increasing heat as it dries out and its thorough drying is thereby assured.

After the drying operation is completed and the strip comes off from the drum 16, 75 passing through a slot provided for this purpose in the scraper 20, as shown in Fig. 3, it enters the rolling machine and is rolled and compressed before it passes out of the drying box, thereby finishing the article 80 without subjecting it to any sudden changes in temperature. The rollers 28 and 29 of the rolling machine are mounted upon the inner ends of two parallel shafts 30 and 31 which extend horizontally into the dry- 85 ing box in front of the lower drum 16 at the end from which the dried strip passes off the drum, and these shafts bear in frames 32 and 33 outside of the drying box which are supported upon a bracket 34 on the side 90 of the box. The lower shaft 31 is mounted in stationary bearings and the upper shaft 30 is mounted in vertically-adjustable bearing blocks, the vertical position of which is controlled by adjusting screws 35, suitable 95 locking nuts 36 being provided to lock the screws in adjusted position. By these means the roller 28 may be made to approach its complementary roller, more or less, and the compression upon the dried strip be thereby 100 adjusted.

The roller 28 has a circumferential tongue which fits into a complementary groove in the periphery of the roller 29, and the dried strip as it comes off the drum 16 is passed 105 through the groove in the roller 29 and is compressed and shaped. It is apparent that the tongue and groove may have either transversely flat or curved engaging surfaces, as is desired. 110

The rollers 28 and 29 are driven in opposite directions, by intermeshing pinions 37 on the shafts 30 and 31, the lower shaft 31 being driven from the drum 16 by a sprocket chain 38 which passes around a sprocket 115 wheel 39 on the end of the shaft 31 and around a sprocket wheel 40 on the end of the drum shaft. The sprocket wheels 39 and 40 are so proportioned in size that the rollers 28 and 29 are driven at the same rate, that 120 is, at the same peripheral speed as the drum 16, and the tension upon the strip as it passes through the rolling machine is therefore the same as it is when passing over the drums. 125

After passing through the rolling machine, the finished strip emerges from the drying box through a slit 41 in front of the box, and from thence to a suitable reel 42 on which it is wound, the reel being driven by a belt 43 which passes around a pulley 130

44 on the shaft 30 and over a pulley 45 on the reel, the friction of the belt being such that it will slip as the size of the roll of featherbone increases on the reel, and will 5 therefore at all times rotate the reel just fast enough to wind up the finished strip.

The drying box is provided on its front with hinged doors 46 which meet at the middle and are provided with suitable locking 10 means, and which extend from the top well down toward the bottom of the box, the lower part of the front being provided with a removable portion 47 secured in place by slide bolts, in the usual way, thus the front 15 of the drying box can be opened and access readily had to its interior.

It is obvious that various modifications may be made in the construction shown in the drawings and above particularly de- 20 scribed, within the principle and scope of my invention.

I claim:—

1. Featherbone making apparatus comprising a drying box provided with a source 25 of heat, a plurality of drums rotatively mounted therein and arranged to receive and

convey a continuous strip of sized material passed successively around them, a rolling device disposed within the drying box and arranged to receive the dried strip as it 30 comes from the drums, and means for driving one of the said drums and the rolling device at the same rate.

2. Featherbone making apparatus comprising a drying box provided with a source 35 of heat, a plurality of drums rotatively mounted therein and arranged to receive and convey a continuous strip of sized material passed successively around them, guide members adapted to properly guide the 40 strip over the drums, a rolling device disposed within the drying box and arranged to receive the dried strip as it comes from the drums, and driving means for the rolling device arranged outside the driving box. 45

In witness whereof, I subscribe my signature, in the presence of two witnesses.

JOSEPH W. SCHLOSS.
